TIRE

John O. Antonson, Tallmadge, Ohio, assignor to The B. F.
Goodrich Company, New York, N.Y., a corporation
of New York

Filed May 2, 1966, Ser. No. 2,079

Term of patent 14 years

(Cl. D90—20)

FIG. 1

FIG. 2

FIG. 3

FIG. 1 is a perspective view of a tire showing my new design, it being understood that the tread and sidewall patterns shown in full lines are repeated throughout the circumference of the tire, the opposite side of the tire being identical to that illustrated;

FIG. 2 is an enlarged fragmentary top plan view of a portion of the tire shown in FIG. 1; and

FIG. 3 is a fragmentary transverse sectional view through the tire taken substantially on the plane indicated by the line 3—3 of FIG. 2.

I claim:

The ornamental design for a tire, substantially as shown and described.
